Specification for Design.

Patented July 19, 1921.

Application filed February 2, 1920. Serial No. 355,770. Term of patent 7 years.

To all whom it may concern:

Be it known that I, OSCAR B. FISH, a citizen of the United States, and a resident of Castleton Park, St. George, Staten Island, in the county of Richmond and State of New York, (whose post-office address is 64 East 11th street, New York, N. Y.) have invented a new, original, and ornamental Design for Pen and Pencil Holders, of which the following is a specification, reference being had to the accompanying drawings, forming a part thereof.

Referring to the drawings: the figure is a plan view of a pen holder embodying my new design.

I claim:

The ornamental design for a pen and pencil holder as shown.

OSCAR B. FISH.
